CORSET

Marian Lavington Jacks, London, England

Application November 3, 1937, Serial No. 172,596
In Great Britain August 30, 1937

3 Claims. (Cl. 2—43)

This invention relates to corsets such as are intended for maternity wear.

The object of the invention is to provide a corset which is suitable for use for maternity wear, which offers all the necessary adjustments, and which moreover can be removed when required without the necessity of altering a previous adjustment of the corset but merely by the act of opening a slit in the body part of the corset the effect of which is to loosen the corset upon the wearer such that it can be removed.

In the accompanying drawings:

Figure 1 is a front elevation of a corset in accordance with the invention,

Figure 2 is a similar view but showing the front of the corset partly turned over to reveal a portion of the back and having the bottom portion of the corset broken away, and

Figure 3 is a similar broken away view looking on the inside of the back of the corset.

According to one form of the invention as illustrated in the drawings a maternity corset which is relatively deep for the purpose of providing adequate support for the abdomen has its front portion formed by an upper part 1 which, in depth, extends from the top edge of the corset to, approximately, two-thirds the depth of the corset and by a divided bottom part 2 which, in depth, extends substantially for the remainder of the depth of the corset, this bottom part being constituted by a pair of flaps which are formed from elastic material, so that the flaps are extendible as to length and which are secured to the opposite edge portions of the side and back 3 of the corset, as by stitching. The adjacent free edges 4 of the flaps are connected together by a lacing 5, and these edges are provided with eyelet holes for the passage of the lacing and the lacing provides additional means for adjustment of the effective length of the flaps. The upper part 1 of the front of the corset is preferably formed from non-elastic material and is secured along its longitudinal edges to the opposite edges of the remainder 3 of the corset by lacings 6, the adjacent edges being provided with eyelet holes for the passage of the laces. The centre of the upper front piece 1 is separable by a slit extending from the top edge thereof downwardly to a point approximately, two-thirds of its depth, and the slit is fitted with an interlocking slider type fastener 7 whereby this slit may be opened or closed at will. The arrangement enables the corset to be removed without the necessity of disturbing the setting of the side laces 6 since opening of the slit provides for an increase in the circumference

of the upper part of the corset sufficient to enable the corset to be removed. The side edges of the top part 1 and the adjacent edges of the remainder of the corset, which receive the laces just mentioned, may conveniently have an insert piece 10 secured therebetween which serves as a backing for the lacing and eyelet holes, this insert piece being of such width that it is adaptable to a fully expanded condition of the corset as a consequence of adjustment of the side laces 6. 10 The sliding fastener is also conveniently provided with a backing 8 constituted by a flap secured to the rear of one edge which constitutes the slit. In order to maintain the free edge portion of this flap 8 in position and to prevent ruckling thereof the latter may be fitted with an eye 9 on its front surface for the reception of a hook 10 carried at the free end of an elastic or other strap 11. When the strap is secured in position, it extends transversely between the flap and the lateral edge 20 of the divided portion of the front part which is opposite the edge thereof to which the flap is secured, and the opposite end of the strap is secured to this edge. The backing for the sliding fastener constituted by this flap may conveniently be provided on its rear surface with velvet or other soft finish material and similar soft insertions may be provided as backings for longitudinal stiffeners 12 which are provided in the back portion of the corset. 30

A further corset according to the invention is of similar construction to the corset above described but is formed from interwoven elastic thread so that the material of the corset resembles a closely woven net material. The back portion of the corset, and also the front flaps, are allowed to retain their elasticity circumferentially but the upper front part is rendered inelastic by the securing of an inelastic backing thereto. 35

It is to be understood, however, that the invention is not limited to the use of any particular material for the construction of the corset since silk, satin and other materials may be employed. 40

A corset in accordance with the invention may have its front constituted only by a single piece, corresponding to the upper front part above mentioned, which front part is secured along its longitudinal edges to the adjacent edges of the remainder of the corset by laces and also has a central longitudinal slit containing an interlocking slider type fastener. 45

In any form of the invention the slit above referred to may be disposed otherwise than centrally upon the front of the corset so long as provision is made for increasing the opening at the 55

top of the corset to enable the corset to be removed without the necessity of loosening the side laces.

A corset constructed as above may, if desired, 5 be provided at the centre of the back of the corset and on the inside thereof with a pad 13 which may conveniently have longitudinal stiffening strips 14 enclosed therein, and which pad offers a certain amount of additional support to the 10 back of the wearer while relieving the back of the direct pressure of the stiffeners due to the presence of the pad, which is composed of some soft substance and may extend approximately half way down the back of the corset from the top 15 thereof. The stiffeners when present in the pad (which may be secured to the corset by stitching, for example) may be additional to stiffeners provided in the back of the corset, and corsetry constructed in accordance with the invention may 20 have the pad omitted therefrom if desired.

I claim:

1. A maternity corset comprising in combination, a part adapted to embrace a portion of the back and the sides of the wearer, a composite 25 front part adapted to afford support for the abdomen and comprising an upper part having a central longitudinal slit extending from and including the upper edge thereof and a lower part in the form of a pair of flaps each secured only 30 to the front edge of each said combined back and side supporting part, adjustable means for connecting the contiguous edges of the said flaps, adjustable means connecting the outer longitudinal edges of the upper front part with the adjacent 35 longitudinal edges of the said combined side and

back supporting part, and means for closing and opening the said slit at will.

2. A maternity corset comprising in combination, a part adapted to embrace a portion of the back and the sides of the wearer, a composite front part providing a support for the abdomen including an upper part having a longitudinal slit extending downwardly from the upper edge thereof and a lower part in the form of a pair of elastic flaps stretchable in directions circumferentially of the wearer, each of said flaps being permanently secured to a front edge only of said combined back and side part, adjustable means connecting the contiguous edges of said flaps, adjustable means connecting the outer longitudinal edges of the upper front part with the adjacent longitudinal edges of the combined side and back part, and means for closing and opening said slit. 5 10 15

3. A maternity corset comprising in combination, a part adapted to embrace a portion of the back and sides of the wearer, a composite front part providing a support for the abdomen including an upper part having a central longitudinal slit extending downwardly from the upper edge thereof and a lower part in the form of elastic flaps stretchable in directions circumferentially of the wearer, one flap being stitched to each front edge of the combined back and side part, a non-stretchable lacing connecting the contiguous edges of the flaps, lacings connecting the outer longitudinal edges of the upper front part with the adjacent longitudinal edges of the combined side and back part, and means for closing and opening said slit. 20 25 30
